UNITED STATES PATENT OFFICE.

IMRE DRAPCSATY, OF BARBERTON, OHIO.

WRENCH.

1,119,348.

Specification of Letters Patent.

Patented Dec. 1, 1914.

Application filed September 21, 1914. Serial No. 862,769.

To all whom it may concern:

Be it known that I, IMRE DRAPCSATY, subject of the Emperor of Austria-Hungary, residing at Barberton, in the county 5 of Summit and State of Ohio, have invented certain new and useful Improvements in Wrenches, of which the following is a specification.

This invention relates to certain new and 10 useful improvements in wrenches.

The primary object of the invention is to provide a slideable bolt-locking means for the movable jaw of a wrench whereby said jaw is locked in any relative position with 15 respect to the handle-carried jaw and is automatically releasable upon operating a spring catch device.

A further object is to provide a means for releasing the movable jaw member of a 20 wrench for free actuation when desired, the same being capable of being readily locked in any desired adjusted position.

A still further object is the provision of a housing hinged to a handle having a jaw 25 at one end thereof and providing a slideable jaw member within said housing adapted to be locked in its adjusted position within said housing by means of a sliding bolt while a releasable catch allows for the automatic release of the said movable jaw member.

With these general objects in view and others that will appear as the nature of the invention is better understood, the same 35 consists in the novel combination and arrangement of parts to be hereinafter more fully described, illustrated in the accompanying drawings and set forth in the appended claim.

40 In the drawing forming a part of this application and in which like-designating characters refer to corresponding parts throughout the several views, Figure 1 is a side elevation of the device partially broken away. Fig. 2 is a front elevation thereof. Fig. 3 is a central longitudinal section taken on line III—III of Fig. 2, showing the housing and locking bolt, the adjacent elements being shown in side elevation, and 45 broken away. Fig. 4 is a transverse sectional view on line IV—IV of Fig. 1 taken centrally through the housing with the device in its locked position. Fig. 5 is a similar view taken on line IV—IV of Fig. 1 50 with the elements in their unlocked positions. Fig. 6 is a transverse sectional view

taken upon lines VI—VI of Fig. 1, and Fig. 7 is a perspective view of the locking bolt.

Referring more in detail to the drawing, 60 the handle 10 of the wrench is provided at one end with a serrated jaw 11 and has a housing 12 pivoted thereto by the pin 13 which extends through the adjacent portion of the handle and through the opposite 65 spaced extension plates 14 of the housing. A jaw 15 is movably mounted and is provided with a serrated face 16 positioned opposite the jaw 11 and has a shank 17 slidably positioned within the housing and between the plates 14 thereof and also between the inner wall 18 of the housing and the adjacent edge 19 of the wrench handle. Opposite fingers 20 are secured to the jaw handle and project upon opposite sides of 70 the jaw shank 17 acting as guides therefor, while a helical spring 21 is secured to the handle edge 19 and bears upon the adjacent edge of the shank 17 which tends to normally hold the two jaws resiliently toward 75 each other or in engagement with any work positioned therebetween.

The housing 12 is provided with a transverse opening 22 therethrough and in which the bolt 23 is slidably positioned, one end 80 thereof being adapted to project within the chamber 24 of a laterally projecting casing 85 25 of the said housing, while the opposite end of the bolt is slideable through an opposite opening 26 of the housing. A lug 27 is 90 carried by the housing and extends into a side slot 28 of the bolt and whereby the sliding inward and outward movements of the bolt be limited. A helical expansion spring 29 is provided within the casing bore 95 24 and engages the inner end of the bolt, tending to normally hold the bolt projected in its unlocked position as shown in Fig. 5.

The jaw shank 17 is provided with a toothed outer face 30 and across which face 100 the bolt 23 is adapted to slide. The said bolt is provided upon substantially one-half of its face which is adjacent to the said jaw shank with teeth 31 which engage the toothed face 30 of said shank when the 105 bolt is positioned inwardly as illustrated in Fig. 4, and at which time as will be evident, the spring 29 will be compressed and the engagement of the teeth of the bolt with the toothed face of the movable jaw shank lock 110 the said shank to the housing.

A socket 32 is provided in the bolt 23 upon

the face thereof opposite its slotted face and within which socket a catch rod 33 is adapted to seat when the bolt is positioned in locking engagement with the jaw shank as 5 illustrated in Figs. 3 and 6. A catch plate 34 is pivoted within a side recess 36 of the housing and has the rod 33 pivoted to its inner end and slidably extending through a perforation 37 of the housing, which per- 10 foration 37 connects the recess 36 with the housing opening 22. An expansion spring 38 positioned beneath the pivoted plate 34 normally holds the rod 33 projected in- 15 wardly and in engagement with the adja- cent side of the bolt when the same is pro- jected, but holds the same within the socket 32 when the bolt is inclosed and in its locked position.

From this detailed description of the in- 20 vention, it will be apparent that in the op- eration thereof, when the bolt is in its un- locked position as shown in Fig. 5, the shank of the jaw 15 may be freely moved longi- 25 tudinally through the housing until the jaws are brought into engagement with the work, when a pressure upon the outer end of the bolt moves the same inwardly com- 30 pressing the spring 29 and engaging the teeth of the bolt with the toothed face of the shank which locks the wrench upon the work, and in which position the catch rod 33 engages the bolt socket 32 and retains the bolt so locked. When desired to release 35 the bolt, the outer end of the catch plate 34 is depressed for compressing the spring 38 and the catch rod is thus withdrawn from the bolt socket and the release of the bolt allows the spring 29 to project the same so that the untoothed surface or cut-away por- 40 tion 39 of the bolt will be positioned ad- jacent the toothed face of the shank so that such shank will be released and may be freely moved longitudinally for again ad- justing its jaw 15.

Copies of this patent may be obtained for five cents each, by addressing the "Commissioner of Patents, Washington, D. C."

While I have shown and described the 45 preferred embodiments of my invention, minor changes may be made without de- parting from the spirit and scope of the in- vention as set forth in the claim.

What I claim as new is:

A wrench comprising a handle, a hous- 50 ing, spaced plates upon said housing pivoted to said handle, a jaw shank slidably mounted between said plates and having a toothed face adjacent the inner side of said 55 housing, the said housing having a trans- verse opening therethrough opening into the space formed between the said plates, a hollow casing at one side of the housing having a chamber in alinement with said 60 opening, a bolt positioned within said open- ing and chamber and slidably mounted therein, teeth projecting from a portion of the face of said bolt lying adjacent to said shank, the remaining portion of said bolt 65 face being cut away, an expansion spring within said casing chamber engaging said bolt and normally projecting the same, the said bolt having a slot at one side and a 70 socket in its opposite side, a lug carried by said housing and projecting within the said bolt slot, the said housing having a side re- cess therein and a perforation communicat- 75 ing between said recess and the housing opening, a spring-pressed catch plate pivot- ed within said recess, and a catch rod hinged to the inner end of said catch plate and slidably positioned through the said perfora- 80 tion and adapted for entering the said bolt socket when the bolt is in its retracted lock- ing position with its teeth engaging the toothed face of the jaw shank.

In testimony whereof I affix my signature in presence of two witnesses.

IMRE DRAPCSATY.
